UNITED STATES PATENT OFFICE.

EDWARD L. ACKERMAN AND CLARENCE P. CHAMBERLIN, OF DETROIT, MICHIGAN,
ASSIGNORS TO JOS. N. SMITH COMPANY, OF DETROIT, MICHIGAN, A CORPORATION
OF MICHIGAN.

FASTENER FOR AUTOMOBILE-HOODS.

1,151,986.

Specification of Letters Patent. Patented Aug. 31, 1915.

Application filed July 1, 1914. Serial No. 848,394.

To all whom it may concern:

Be it known that we, EDWARD L. ACKERMAN and CLARENCE P. CHAMBERLIN, citizens of the United States of America, residing at Detroit, in the county of Wayne and State of Michigan, have invented certain new and useful Improvements in Fasteners for Automobile-Hoods, of which the following is a specification, reference being had 10 therein to the accompanying drawings.

Our invention relates to fasteners for automobile hoods and has among the objects thereof to provide a simple and efficient construction for securing the hood in its 15 closed position; to provide a device which will not rattle; to provide a structure by which a retaining bearing for the lower edge of the hood is had; and further to provide a fastener which is permitted a universal 20 movement.

Other objects of the invention will more fully hereinafter appear.

The invention resides in the construction, arrangement and combination of parts as 25 hereinafter set forth.

In the drawings,—Figure 1 is a side elevation of a device embodying the invention, showing the same as applied to a hood; and Fig. 2 is a perspective view of the fastener. 30 A designates the hood of an automobile, and B is a knob or button thereon.

C is the latch member composed of a handle portion D and a chambered portion E.

Within the chamber E is arranged a 35 spring F that is sleeved upon a bolt G. The upper end of the bolt is provided with a head I for engaging one end of the spring F, while the opposite end of the spring seats against an inwardly-extending flange J spun 40 on the lower end of the chamber E. The chamber E is preferably cylindrical and the handle D is preferably formed wide and flat, terminating at its upper end in a hook-shaped portion or finger-hold K.

45 L is an aperture in the handle portion for engaging the button B.

The lower end of the member G projects for a slight distance without the chamber E and has a head M. The inner face N of the 50 head is rounded to engage a rounded socket O in an attaching clip P. The clip P is slotted as at Q to permit the head M to be engaged with the socket O, the slot Q being of a size to receive the bolt G but being of 55 lesser cross-section than the cross-section of

the head M, so that when the head is engaged with the socket, it can be withdrawn therefrom only by a lateral movement.

R is a flange extending laterally from the clip P and this flange is curved upwardly to 60 form a suitable seat for engaging the lower edge of the hood A, this hood edge being usually beaded, as indicated by S. In use, after the head M is engaged with the socket O, the clip P is attached to the frame T of 65 the vehicle as by means of screws which pass through apertures V in laterally-extending ears W on the member P. The clip P is so positioned that the seat R is in proper relation to engage the lower edge or bead S of 70 the hood A. To secure the hood the operator draws upwardly on the handle D to engage the apertured portion L over the button B. When so engaged, the spring F will yieldably press the lower edge of the 75 hood A against the seat R, and this seat will hold the lower edge of the hood against lateral movement, thereby insuring proper engagement at all times between the fastener and the button B. As before stated, the 80 head M has the inner face N thereof rounded to engage the rounded seat O. This forms a connection between the clip P and the bolt G that will permit a universal movement between these parts, thereby avoiding 85 any tendency to rupture the fastener by a sudden twisting strain.

The latch member C is preferably formed from tubular stock, the wide, flat handle D being made by flattening the tube. This arrangement not only facilitates manufacturing the article but also gives the desired strength and rigidity to the handle portion D, since the latter is formed of two-ply metal. 95

What we claim as our invention is:—

1. A fastener composed of a member having a chamber and provided with a portion forming a handle, a spring-pressed bolt slidably arranged within said chamber and having a head projecting therewithout, a clip provided with a lateral slot for receiving the head of said bolt, and a laterally-extending portion on said clip forming a bearing, for the purpose described. 100

2. The combination with a frame and a hood, of a fastener comprising a member having a chamber and provided with a portion forming a handle, a spring pressed bolt slidably arranged within said chamber, a 110

clip to which said bolt is secured having a bearing portion for retaining the lower edge of the hood against lateral movement, and a stud and aperture connection between said

hood and fastener. with said frame, and a pin and slot connection between said hood and fastener for holding the lower edge of the hood from vertical movement while in engagement with said bearing seat.

3. The combination with a frame and a hood, of a fastener comprising a member having a chamber and a handle, a spring-pressed bolt slidably arranged within said chamber, a bearing seat for receiving and retaining the lower edge of the hood against lateral movement when the hood is engaged

In testimony whereof we affix our signatures in presence of two witnesses.

EDWARD L. ACKERMAN.

CLARENCE P. CHAMBERLIN.
